ATTORNEYS

UNITED STATES PATENT OFFICE.

DAVID A. LYNN, OF ST. LOUIS, MISSOURI.

SASH FASTENER.

Application filed December 14, 1922. Serial No. 606,889.

To all whom it may concern:

Be it known that I, DAVID A. LYNN, a citizen of the United States, residing at St. Louis, Missouri, have invented a certain new and useful Improvement in Sash Fasteners, of which the following is a full, clear, and exact description, such as will enable others skilled in the art to which it appertains to make and use the same.

This invention relates to sash fasteners of the general type disclosed in my prior U. S. Patent No. 1,125,356, for sash fastener, dated January 19, 1915, and has for its main object to provide a sash fastener of the general type referred to, which is so constructed that the locking element will not project forwardly a considerable distance from the sash which carries it when said locking element is in its inoperative position, and thus strike against and damage the window shade or window curtain when the sash is raised.

Another object is to provide a sash fastener of the general type referred to in which the locking element is so constructed that after it has been moved into its operative position gravity causes said locking element to assume and remain in such a position that it cannot be rendered inoperative by shaking or jarring either sash of the window. Other objects and desirable features of my invention will be hereinafter pointed out.

Figure 1 of the drawings is a front elevational view of a window equipped with a sash fastener constructed in accordance with my present invention.

Figure 2 is a vertical sectional view through portions of the side rails of the top and bottom sash, showing the locking element arranged in its operative position for locking the sash together in such a way that neither sash can be opened; and

Figure 3 is a front elevational view of a portion of the bottom sash, showing the locking element arranged in its inoperative position.

Referring to the drawings which illustrate the preferred form of my invention, A and B designate the top and bottom sash of a window and C designates as an entirety

a locking element carried by the bottom sash and adapted to be engaged with the top sash so as to lock said sash either in a completely closed or partially open position. Instead of making the locking element C in the form of a long bolt that projects forwardly a considerable distance from the bottom sash when said locking element is disengaged from the top sash, as in the sash fastener that forms the subject-matter of my prior patent previously referred to, I prefer to form the locking element C from two parts 1 and 2 hinged or pivotally connected at 3 so as to permit the part 2, which I will refer to as the operating portion of the locking element, to be arranged in a vertical position parallel to and in close proximity to the front side of the bottom sash B when the locking portion 1 of said element C is disengaged from the top sash A. The locking element C is reciprocatingly mounted in the bottom sash B in such a way that the locking portion 1 of said element can be inserted in an aperture D in the top sash when it is desired to lock the sash in their closed position or inserted in one of a plurality of apertures D' in said top sash when it is desired to lock the sash in a partly open position, the same as in the sash fastener described in my said prior patent, but when the locking element is in its inoperative position, the front portion 2 of same will not project forwardly from the bottom sash B a considerable distance, and thus strike against the window sash or window curtain when the bottom sash of the window is raised. On the contrary, the locking element of my present sash fastener is composed of a jointed member whose parts can either be arranged in longitudinal alignment with each other, when it is desired to lock the sash together, or in a position at right angles to each other when it is desired to release the sash, thereby producing a sash fastener that will not strike against or interfere with the window shade or window curtain during the operation of raising or lowering the sash on which the locking element is mounted.

Any suitable means can be used for pre-

venting the locking portion 1 of the locking element C from being disengaged from the top sash A of the window by shaking or jarring either sash, but I prefer to equip 5 the bottom sash B with a plate or abutment E through which the operating portion 2 of the locking element C passes and provide said operating portion 2 with one or more laterally-projecting pins or stops 4 10 that are arranged on the inner side of the plate E when the locking element C is engaged with the top sash A and which prevents said locking element from moving accidentally out of engagement with the top 15 sash or being disengaged from said top sash by jarring or shaking either sash of the window.

To disengage the locking portion 1 of the locking element C from the top sash A, 20 it is necessary to turn or rotate the locking element slightly so as to bring the pin or pins 4 thereon into alignment with a notch or notches 5 at the sides of the hole in the plate E through which the locking 25 element extends and then pull the locking element C forwardly so as to withdraw the locking portion 1 of same from the aperture in the top sash A. This operation causes the hinge or joint 3 of the locking 30 element C to be positioned in front of the plate E on the bottom sash B of the window, and thereafter, the operating portion 2 of the locking element can be moved into a position at right angles to the locking portion 1, thereby causing said operating portion 2 to be arranged in close proximity to 35 the sash B where it will not interfere with the window shade or window curtain when the bottom sash is raised or lowered.

40 To lock the sash it is necessary to first swing the operating portion 2 of the locking element into such a position that it is in longitudinal alignment with the locking portion 1, then turn said locking element 45 into such a position that the pin 4 thereon is in alignment with the notch 5 in the plate E and thereafter move said locking element rearwardly so as to insert the locking portion 1 of same in one of the apertures D or D' in the top sash A, the locking element coming to rest in such a position that the pin 4 thereon is positioned 50 behind or on the inner side of the plate E. In order to insure the locking element moving automatically into such a position that the pin 4 thereon will be out of alignment with the notch 5 in the plate E when the locking portion 1 of the locking element is in engagement with the top sash A, I prefer 55 to provide the operating portion 2 with a weighted finger piece 2^a that swings downwardly into a vertical position, as shown in Figure 2, thereby turning the operating portion 2 of the locking element into such 60 a position that the pin 4 is out of align- 65

ment with the notch 5 as soon as the operator removes his finger from the finger piece 2^a of the locking element at the completion of the operation of moving said locking element into its operative position. The locking portion 1 of the locking element is preferably of slightly greater diameter than the operating portion 2 of the locking element and the hole in the plate E through which the locking portion 2 passes is made small 70 enough so as to prevent the locking portion 1 from passing through same, thereby causing the plate E to also serve as a means for preventing the portion 1 of the locking element C from being completely withdrawn from the bottom sash B of the window. 75

A sash fastener of the construction above described is inexpensive to manufacture; it is easy to install; it will effectively lock 80 two window sash either in a closed position or partially open position; and the locking element C of same is of such construction that when it is in its inoperative position, the front portion of same will extend parallel to the bottom sash B in close proximity to same, and consequently, will not strike against the window shade or curtain when the bottom sash is raised or lowered, said locking element being of such design that gravity causes it to assume a position wherein it cannot be accidentally disengaged from the top sash or disengaged from said top sash by jarring or shaking either sash of the window. 90

Having thus described my invention, what I claim as new and desire to secure by Letters Patent is:

1. A window sash fastener, comprising a 105 slideable locking element mounted in a window sash and adapted to be inserted in an aperture in a co-operating sash to lock the sash together, a stop on said locking element, an abutment co-operating with said stop to prevent said locking element from 110 being withdrawn from said aperture, and a weighted portion on said locking element for causing it to automatically assume such a position that said stop is arranged in operative relationship with said abutment. 115

2. A sash fastener, comprising a locking element slidably mounted in a sash and composed of a locking portion and an operating portion hinged or pivotally connected together, a stop on said operating portion, an abutment on the sash that is adapted to co-operate with said stop to prevent the locking element from being moved into an inoperative position, and a weighted part 120 on said operating portion for automatically turning said operating portion into such a position that said stop will co-operate with said abutment. 125

3. A sash fastener, comprising a locking element slidably mounted in a window 130

sash and composed of a locking portion and an operating portion hinged or pivotally connected together, a weighted finger piece on the outer end of said operating portion, 5 a stop on said operating portion, a plate on the sash that co-operates with said stop to prevent the locking element from moving into an inoperative position, and an opening in said plate that forms a clearance for said stop during the operation of positively moving said locking element into its inoperative position. 10
